UNITED STATES PATENT OFFICE.

CHARLES A. READE, OF CHICAGO, ILLINOIS.

HANSOM-CAB.

SPECIFICATION forming part of Letters Patent No. 356,160, dated January 18, 1887.

Application filed April 26, 1886. Serial No. 200,175. (No model.)

To all whom it may concern:

Be it known that I, CHARLES A. READE, a citizen of the United States, residing at Chicago, in the county of Cook, State of Illinois, 5 have invented certain new and useful Improvements in Hansom-Cabs, of which the following is a specification.

My invention relates to hansom-cabs such as have curved doors, and has for its object to 10 provide a cab with such curved doors as will be more easily and cheaply made, and will permit the center of the dash-board and the center of the front to come closely together, while permitting the curved doors to swing 15 easily. I attain these objects by the means illustrated in the accompanying drawings, wherein—

Figure 1 is a side and interior view of a cab, and Fig. 2 is a top view. Fig. 3 is a detail.

20 Like parts are indicated by the same letter in the figures.

A is the body; B, the rear elevated seat; C, the inner seat; F, the dash-board, curved, as shown, and somewhat in the form of the front 25 when the doors are curved.

G is the narrow connecting part of the dash-board, and in some cases the two sides of the board may come together, and thus the connecting-piece be disposed of.

30 H H are the curved doors, shaped as shown, forming a convex curve until toward the forward edge, where the curve becomes concave, and of such shape that the two forward edges of the doors will almost form an apex or edge 35 if brought together.

I I are the cab-windows.

J is the top, curved forwardly so as to accommodate itself to the shape of the doors.

G is the center-post, and to it the doors may 40 be hinged, or they may fold against it. The center-post is at once the center of the front and dash-board. It supports the top and doors.

O is the step, and N is a continuously- 45 curved rod, as shown, in the meeting sides of which the step-shank P is secured.

S S are the branches of the hinges, one se-

cured to the door, the other to the body, and both pivoted together. A cylindrical box containing the spring T forms part of the hinge, and the spring tends to close the door. 50

The use and operation of my invention are as follows: The center-post serves to support the top, and acts also as the hinge-post of the doors when they swing forward, and as the door-frame when they swing rearward, as shown. At the same time it acts as the dash-board support and center. By this means the cab front is made simpler and lighter and with less expense than usual. The peculiar 60 curve given to the forward part of the doors permits them to act substantially as doors having a uniform and continuous curve, while at the same time they give to the cab the appearance of having a prow-shaped front. The use 65 of the step will be obvious. The peculiar arrangement of the door hinge and spring serves to keep the door constantly closed and to close it when it is opened.

I claim—

1. In a hansom-cab, the combination of the body with hinged swinging curved doors, a curved dash-board, and a central forward post, which serves as a support for the top and the dash-board and to receive the edges of the 75 doors.

2. In a hansom-cab, a step consisting of a curved rod bow-shaped below and attached to the body at each end, with a step and a step-shank which rests in the crotch formed by the 80 meeting sides of the bow-shaped rod and is attached thereto, and which passes thence to the body.

3. In a hansom-cab, the combination, with the body, of doors which are in the main outwardly convex, but which terminate forwardly in outwardly-concave curves, whereby the opening is made larger when the door is open, and the danger of encountering the angle of the door by the person entering is obviated. 85

CHARLES A. READE.
